US0D1048944S

(12) **United States Design Patent** (10) Patent No.: **US D1,048,944 S**
(45) Date of Patent: ** Oct. 29, 2024

(54) **MOTOR SCOOTER AND/OR REPLICA THEREOF**

(71) Applicant: **Honda Motor Co., Ltd.**, Tokyo (JP)

(72) Inventors: **JingWen Kuang**, Shanghai (CN); **Bin Han**, Shanghai (CN); **Kenji Watanabe**, Shanghai (CN)

(73) Assignee: **HONDA MOTOR CO., LTD.**, Tokyo (JP)

(**) Term: **15 Years**

(21) Appl. No.: **29/885,739**

(22) Filed: **Feb. 28, 2023**

(30) **Foreign Application Priority Data**

Sep. 1, 2022 (JP) ..... 2022-018769 D

(51) **LOC (14) Cl.** **12-11**

(52) **U.S. Cl.**

USPC **D12/110**

(58) **Field of Classification Search**

USPC D12/110, 111, 117; D21/432, 538

(57) **CLAIM**

The ornamental design for a motor scooter and/or replica thereof as shown and described.

DESCRIPTION

FIG. 1 is a first perspective view of a motor scooter and/or replica thereof, showing my new design;

FIG. 2 is a second perspective view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines shown in the drawings depict portions of the motor scooter and/or replica thereof that form no part of the claimed design.

1 Claim, 7 Drawing Sheets
